UNITED STATES PATENT OFFICE.

PAUL A. MEEHAN, OF CLEVELAND, OHIO, ASSIGNOR TO AMERICAN DRESSLER TUNNEL KILNS, INC., COUNTY OF CUYAHOGA, OHIO, A CORPORATION OF NEW YORK.

OPEN FIRE KILN.

Application filed August 21, 1924. Serial No. 733,306.

The general object of my present invention is to provide an improved door arrangement for the exit end of a continuous tunnel kiln. More specifically, the object of my invention is to provide kiln exit doors of simple construction and comprising simple, reliable and effective provisions for normally locking the door parts in their closed position and for effecting the automatic release and opening of the doors on the engagement therewith of the kiln cars as the latter successively approach the exit end of the kiln at the end of their travel through the latter.

The various features of novelty which characterize my invention are pointed out with particularity in the claims annexed to and forming a part of this specification, but for a better understanding of the invention, its advantages, and specific objects attained with its use, reference should be had to the accompanying drawings and descriptive matter in which I have illustrated and described a preferred embodiment of my invention.

25 Of the drawings:

Fig. 1 is a sectional elevation of a portion of a continuous tunnel kiln equipped with my invention;

Fig. 2 is an end elevation of the exit end kiln doors;

Fig. 3 is a section on the line 3—3 of Fig. 2; and

Fig. 4 is a section on the line 4—4 of Fig. 2.

35 In the drawings A designates a somewhat conventionally illustrated tunnel kiln having a heating zone A' with combustion chambers B at the sides thereof, a cooling zone A², and exit doors E and EA at the exit end of the cooling zone section of the kiln. As shown, the two doors E and EA are substantially similar in construction and are each connected by hinges E' to the corresponding side portion of the door frame. The doors as shown are formed of metal plates suitably reinforced by stiffening bars. The upper edges of the doors overlap the lintel portion of the door frame, and their lower edges overlap a door sill member F which is slotted for the passage of the kiln track rails C, and for the kiln car wheel flanges. The door E is provided at its free edge with a cover plate E² overlapping the free edge of the door EA.

45 The door E is also provided with a series

of guides E³ for vertical removable upper and lower bolts or locking bars G and g, respectively. The doors are locked in their closed position by moving the bars G and g up and down, respectively, into engagement 60 with the corresponding keepers H and h, secured to the lintel and sill portions, respectively, of the door frame. The bars G and g are advanced and retracted by means of a lever I pivoted at I' in brackets E⁴ secured 65 to the door E. The lever I is connected to the adjacent ends of the bars G and g at opposite sides of its pivot I' by links or connecting rods J. The lever I comprises a portion extending through a slot in the door 70 E and provided at the inner side of the door with a curved shoe or bearing portion i engaged by the front end of a kiln car moving into proximity with the exit end of the kiln. As the motion of the car toward the 75 exit end of the kiln continues the lever portion i is engaged and the lever I is turned on its pivot and thereby retracts the locking bars G and g and releases the doors E and EA before the approaching kiln car 80 comes into direct engagement with the doors.

Each of the doors E and EA is provided with a horizontal bearing in the form of a bar E⁵ engaged by the car body as the movement of the latter continues after tilting the 85 lever I to unlock the doors. The continued movement of the car after engaging the bars E⁵ will gradually open the doors. The fact that the slide bars E⁵ project into the kiln 90 farther than do other portions of the doors when the latter are closed tends to prevent engagement of the upper portions of the doors by material (not shown) which may be loaded on the car.

In the regular intended operation of the 95 kiln as soon as an approaching car releases the doors E and EA the latter are manually opened by a kiln attendant who connects the car to external door operating provisions which pull the car out of the kiln far enough 100 to permit the doors to be again manually closed and locked in place. The movement and position of the external end of the lever I indicates to the attendant the time when the car should be thus removed. Should the 105 signal indication thus made be overlooked or for some other reason is not responded to, the continued movement of the train of cars in the kiln slowly pushes the front car out of the kiln, and the simple and effective 110

door releasing and operating provisions disclosed effectively prevent injury to the cars and doors which would result if no such provisions were employed. The damage 5 otherwise possible under such circumstances has heretofore led to the use of electrical control provisions much less simple, expensive and reliable than the door releasing provisions illustrated herein.

10 E⁶ represents a latch pivotally connected to the door and operating to prevent the bar G and thereby the bar g from being advanced accidentally or by the weight of the lever I while the doors are open. This latch 15 may be manually released to permit the doors to be locked in place by simple lifting the free outer end of the latch.

While in accordance with the provisions and statutes I have illustrated and described 20 the best form of my invention now known to me it will be apparent to those skilled in the art that changes may be made in the form of apparatus disclosed without departing 25 from the spirit of my invention as set forth in the appended claims and that certain features of the invention may sometimes be used without a corresponding use of other features.

Having now described my invention what 30 I claim as new and desire to secure by Letters Patent is:

1. The combination with a continuous tunnel kiln, of a door for the exit end of the kiln and a locking mechanism for securing the door in its closed position comprising a mechanical releasing part mounted 35 on the door and projecting into the kiln in the path of an approaching car and adapted to be operated by the car as the latter approaches the kiln door.

2. The combination with a continuous tunnel kiln, of the door for the exit end of the kiln and a locking mechanism for securing the door in its closed position including mechanical actuating means mounted 45 on the door and comprising a part external to the latter by which the door may be manually locked in place or released and a part at the inner side of the door adapted to be 50 engaged by an approaching car and thereby operated to release the door.

3. The combination with a continuous tunnel kiln and a locking mechanism for securing the door in its closed position comprising an actuating lever mounted on the 55

door and projecting through the latter and having an external portion manually operable to lock and unlock the door and an internal part adapted to be engaged by an approaching kiln car and thereby actuated to unlock the door.

4. The combination with a continuous tunnel kiln, of an exit door hinge connected to the kiln structure at the side of the latter part and provided with a horizontally elongated bearing surface projecting away from lower portion of the inner side of the door into the kiln beyond portions of the door located at higher levels, said surface being in position to be engaged by the end of the body of an approaching car whereby the latter may push the door open after the latter has been unlocked, and a locking mechanism for the door including a releasing part adapted to be engaged by an approaching car and thereby actuated to release the door.

5. The combination with a continuous tunnel kiln, of a door for the exit end of the latter formed with a slot, vertically movable upper and lower locking bolts mounted on the door, a lever pivotally mounted on the door and extending through said slot into the path of an approaching car, and connections between said bolts and lever whereby the bolts may be advanced or retracted by manual actuation of the external end of the lever and retracted by engagement of an approaching car with the inserted end of the lever.

6. The combination with a continuous tunnel kiln, of exit doors hinge connected to the kiln structure at the sides of the latter and provided with horizontally elongated bearing surfaces projecting away from the inner sides of the doors in position to be engaged by an approaching car whereby the latter may push the doors open after the latter have been unlocked, mechanism mounted on one of said doors for locking the latter in its closed position including a part at the inner side of the door in position to be engaged and thereby released by an approaching kiln car, and means carried by said one door for holding the other door in its closed position when said one door is closed.

Signed at Cleveland, in the county of Cuyahoga, and State of Ohio, this 18th day of August, A. D. 1924.

PAUL A. MEEHAN,
